UNITED STATES PATENT OFFICE.

CHARLES E. SKINNER AND EUGENE TYMESON, OF YONKERS, N. Y., ASSIGNEES TO THE SMITH MOQUETTE LOOM COMPANY, OF SAME PLACE.

LOOM FOR WEAVING TUFTED FABRICS.

SPECIFICATION forming part of Letters Patent No. 288,268, dated November 18, 1883.

Application filed December 21, 1881. (No model.)

To all whom it may concern:

Be it known that we, CHARLES EDWARD SKINNER and EUGENE TYMESON, of Yonkers, in the county of Westchester and State of New York, have made an invention of certain new and useful Improvements in Looms for Weaving Tufted Fabrics; and we do hereby declare that the following, in connection with the accompanying drawings, is a full, clear, and exact description and specification of the same.

This invention has reference to looms for weaving Moquette carpets and similar fabrics, in the weaving of which rows of tufts of colored yarns are inserted in and secured to the body of the fabric; and the object of the invention is to enable the ends of the rows of tufting material inserted from one side of the position of the warp-threads in the loom to be turned toward the side from which they have been inserted, so that both ends of the tufting material may be at the same side of the fabric.

The invention consists of certain combinations of mechanical devices which are recited in the claims at the close of this specification. In order that these combinations may be fully understood, we have represented in the accompanying drawings, and will proceed to describe, certain parts of a loom embodying the invention in the best form at present known to us.

Figure 1 represents a longitudinal section of parts of the loom. Figs. 2, 3, and 4 represent detached portions of the loom.

As the invention has reference to particular portions of the loom, the other parts thereof may be constructed substantially as described and represented in the Letters Patent of the United States No. 186,374, with such variations only as may be necessary by reason of the present invention, as hereinafter set forth.

The warp and the weft threads or filling of the fabric may be held and operated substantially as they are in other Moquette-carpet looms.

The tufting is by preference applied to a series of spools, which are carried by means of chains or other mechanism, and are presented in succession to the devices by which they are brought to and removed from the vicinity of

the fabric for the purpose of having the tufts placed therein. Each spool is fitted in a spool frame or carriage, which is provided with a row of tubes or needles, h , to hold the ends of the tufting material, and the frame should also be provided with a spring-brake to prevent the turning of the spool, except when the tufting material is pulled off it by the operation of the mechanism. In order that the spool-frame may be moved toward and from the place in the loom at which the tufting is to be applied to the warp-threads, the loom is preferably provided with a pair of movable arms, K , (one at each side of the loom,) which are connected with a rock-shaft, K^2 , which is caused to rock, so as to move the ends of the movable arms toward and from the position of the warp in the loom. The movable arms K are preferably provided with clutches to grasp the ends of the spool-frames, and the said arms are preferably connected by pivots with the rock-shaft arms K' , (one for each movable arm,) so that the first may be moved laterally in opposite directions to grasp and release each spool-frame in succession. The said movable arms are caused to move toward and from the position of the fabric by means of a cam, K^3 , operating upon said arms through the intervention of a friction-wheel, K^4 , cam-lever K^5 , rod K^6 , rock-shaft arm K' , and the rock-shaft K^2 , and the lateral movements of the movable arms to enable them to grasp and release the spool-frames may be effected by the same means as is described for that purpose in Patent No. 233,290.

In order that the present invention may be embodied in the loom, it is provided with means for producing a blast or jets of air at the side of the warp opposite that from which the tufting material is introduced, so that the ends of the tufting material (which have been moved to the warp by the movable arms K , and have been introduced between the warp-threads by the tubes h) may be blown backward toward the side of the warp from which they were introduced. The blowing devices obviate the necessity of using a comb, brush, or other mechanical lifter to turn the tufting material upward.

In the example of the invention represented in the accompanying drawings a blast of the requisite force is furnished by a cylinder, A, which is fitted with a piston, B, containing an 5 inlet-passage and a valve, a, for the entrance of air when the piston is drawn backward in the loom. The piston is connected by means of a connecting-rod, b', with a lever, B², which is forced forward at the proper time, in the 10 operation of the loom, by means of a cam, B³, secured to and caused to revolve with the cam-shaft G of the loom, the rim of the cam operating upon a friction-wheel secured to the lever B², and the backward movement of 15 the piston being effected, as the cam permits, by means of a strong spring, B⁴. The air compressed during the advance of the piston in the cylinder is applied to the tufting material by means of an air-pipe, C, which extends 20 crosswise of the loom, beneath the position of the warp m, and is fitted with a series of ajutages from which the air can be ejected in jets. In this instance the air-pipe is supported in the loom by being connected at each 25 end by an arm, c', with the rock-shaft F² of the lay F of the loom, so as to vibrate on said rock-shaft. Each pipe-arm, when in a forward position, (as represented at Fig. 1,) is supported by a bracket, c⁸, connected with the 30 frame of the loom, and when the pipe-arms rest against these brackets the air-pipe C is so far forward in the loom as not to interfere with the operation of the other parts thereof. When the blast of air is to be applied to the 35 tufting material, the air-pipe is moved backward in the loom to place its ajutages in the proper position to operate upon the ends of the tufting material. In order that this movement may be effected by the lay-cam, the lay 40 is fitted at each end with a hook, c⁹, whose point engages with the corresponding pipe-arm, c', and these hooks, when the lay is moved backward after beating up the binding-filling, as hereinafter described, pull the pipe-arms 45 and the air-pipe backward to the proper position for ejecting the air.

The air-pipe C is connected by means of several flexible pipes, c, with the exit-pipe C' of the blast-cylinder A, and the passage of air 50 from the blast-cylinder to the exit-pipe is controlled by a valve, C², constructed to slide in a valve-chest, C³. The valve is fitted with a valve-rod, c', to which a spring, c², is applied, which constantly tends to hold the valve open, 55 and to open it after it is closed. The end c³ of the valve-rod c' is extended backward and is bent sidewise, so that it is within the range of motion of an extension, b², of the blast-lever B²; hence if the valve be open the next succeeding backward movement of the lever B² 60 draws the valve backward in its chest and closes it. In order that the valve may be kept closed until the blast is to be used, the valve-rod c' is fitted with a projection which engages 65 with a latch, c⁴, whenever the valve-rod is moved backward.

The loom, parts of which are represented in the accompanying drawings, is constructed to introduce into the warp of the fabric four shoots of filling or weft thread for each row of tufting material, and consequently the lay-cam F³ is made with four projections, f' f' f' f², to operate the lay for each revolution of the cam-shaft G. Three of these projections, f' f' f', are preferably duplex to impart a double beat 70 to the lay for beating up each shoot of coarse filling. The fourth projection, f², is preferably single-pointed, and operates the lay for beating up a shoot of finer filling for binding the tufting material in the fabric. The blast 80 should be applied to the ends of the tufting-yarns after the shoot of binding-filling is beaten up, and in order to simplify the loom a provision is made for letting on the blast by the movement of the lay F. For this purpose the 85 shank of the valve-latch c' is fitted with a slotted rod, c⁵, whose slotted end fits upon a pin secured to an arm, c⁶, which is projected from the rock-shaft F² of the lay. The slot of the rod is of such length that in the ordinary 90 backward movement of the lay, as permitted by the form of the lay-cam F³, the pin of the arm c⁶ vibrates in the slot without moving the latch-rod c⁵ or the latch c'; but the portion g of the rim of the lay-cam, which controls the 95 backward movement of the lay after the binding filling is beaten up, is depressed more (by being nearer the axis of the cam-shaft) than the residue, so that the lay F may then move backward far enough to cause the pin of the 100 arm c⁶ to move the latch-rod c⁵ and raise the end of the latch c' from the valve-rod c', thereby releasing the valve-rod and valve, and permitting the valve to be opened by the spring c², the result of which is that the compressed 105 air in the blast-cylinder and pipes escapes through the ajutages of the air-pipe C. When the air-pipe C is moved backward with the lay F, as represented in the drawings, the same movement of the lay brings the ajutages of the 110 air-pipe close to the lower ends of the tufting material, so that the blast is directed against 115 said ends by the air-pipe, and they are blown backward and upward into or through the warp, and if these ends are not blown through the warp the raising of the warp-threads at the sides of the tufting material, to form the next succeeding shed for the passage of the filling, raises the said ends high enough to permit the filling-thread to be driven forward beneath them by the action of the lay F.

When the loom is in operation, the tufting material is moved to the warp-threads by the action of the movable arms K, and is introduced between the warp-threads and placed 120 within the range of the blast from the air-pipe C by means of the series of tubes or needles h'. The subsequent action of the blast bends the end of the tufting material backward and upward toward the side of the warp-threads from 125 which the tufting material was inserted, and the lay insures the completion of the operation by 130

beating up the next shoot of filling against the tufting-yarns.

The blast-cam B³ is by preference constructed as represented in the drawings, so as to gradually compress the air and produce the greatest compression just previous to the opening of the blast-valve C². It is not, however, necessary to the invention that the blast should be generated by a cylinder or other blowing device connected with the loom, it being obvious that a blowing-engine separate from the loom may be employed to supply the air-pipe C¹ of the loom or the air-pipes of a number of looms in the same establishment. It is also not essential to the invention that the air-pipe should be carried by the lay and be moved by the lay-cam F³, or that the latch c⁴ and valve C² should be operated by the lay, because special devices may be used to operate the air-pipe and the latch of the valve when the lay has been moved backward in the loom sufficiently to permit the ends of the tufting material to be blown upward; but the connection of the blast-pipe and the valve with the other members, so that they may be controlled by

the lay-cam, is convenient, and obviates the necessity of using additional devices in the loom, thereby rendering it less complex.

We claim as our invention—

1. The combination, substantially as before set forth, of the series of tubes for inserting the tufting material in the warp, with the blast-pipe for directing a current of air against the ends thereof. 30
2. The combination, substantially as before set forth, of the movable arms arranged at one side of the position of the warp, with the air-pipe arranged at the opposite side thereof. 35
3. The combination, substantially as before set forth, of the movable arms at one side of the position of the warp, the air-pipe arranged at the opposite side thereof, and the valve for controlling the exit of air through the air-pipe. 40

Witness our hands this 3d day of December, A. D. 1881.
